FRIEDRICH MERK, OF CHARLOTTENBURG, GERMANY, ASSIGNOR TO SIEMENS & HALSKE, A. G., OF BERLIN, GERMANY, A CORPORATION OF GERMANY.

AUTOMATIC TELEPHONE SYSTEM.

1,132,107.

Specification of Letters Patent. Patented Mar. 16, 1915.

Application filed August 25, 1911. Serial No. 645,977.

To all whom it may concern:

Be it known that I, FRIEDRICH MERK, a subject of the German Emperor, and residing at Charlottenburg, near Berlin, Germany, have invented certain new and useful Improvements in Automatic Telephone Systems, of which the following is a specification.

My invention relates to automatic telephone systems in which talking connections are preferably established between the subscribers' lines by means of a plurality of selector switches and a connector switch adapted to be set by current impulses, a calling line being preferably connected by switching devices, such as pre-selectors, call seekers or the like, with a free first selector.

The invention particularly relates to a system in which there is arranged between the said pre-selector and the first selector a set of repeating relays or a repeater which transfers the current impulses for setting the selectors to the operating and switching magnets of the selectors and connector.

A primary object of my invention is to provide a simple and efficient automatic telephone system, particularly one in which the selectors and connector operate without a so-called side switch. Instead of the side switches I employ at the selector and connector switches of my system relay contacts, care being taken that not only the number of both the contacts and the relays controlling the same is as small as possible, but that the consumption of current for such relays during the connection is small. To this end, according to my invention I connect into the incoming end of the test line, which goes from one selector to the next and from the last selector to the connector, a relay which is maintained energized by a holding current flowing over the test line both during the adjustment of the selector or of the connector and also during the continuance of the connection. This relay controls the releasing circuit of its selector or connector, which is led over a break contact at the armature of the relay, in such manner that the release takes place at the outgoing end of the test line when the holding current flowing over the test line is interrupted.

By allowing a current to flow over the test line in the stated manner when one selector is connected with the next, or the last selector with the connector, I obtain a system very

certain of operation because I prevent a selector being set to the connecting contact of a broken line or of the trunk wire of a selector removed from its place for the purpose of repair or the like.

Another object of my invention is to provide at the said repeater a relay which is itself kept energized, even during the emission of impulses, by a current flowing over the line sending the impulses for setting the selectors, and which holds closed at a make contact the test line going out from the first selector, whereby it maintains a holding circuit for the relay at the incoming end of this test line. When employing pre-selectors which connect the calling line with the first selector, I provide means at the said relay for keeping closed the test line coming from the pre-selector and thereby keeping the pre-selector set.

Further, my system comprises at the calling subscribers' lines a meter operated by a relay at the repeater, said relay being energized after the connector has been set to the required line and preferably after the called subscriber has answered. According to my invention this relay at the repeater is controlled in such manner by additional relays that it is connected to the subscriber's line and can be influenced by the connector only in the pauses between the series of impulses.

Further advantages and details of my invention will be understood from the following description and the accompanying drawings.

In said drawings:—Figure 1 shows the station of a calling subscriber, a pre-selector switch appertaining thereto in the central office, and the repeater connected to the line leading to a first selector switch; Fig. 2 shows a first, second and third selector switch; Fig. 3 shows a connector switch and the station of a called subscriber.

The drawings illustrate only the connection of the system; the switches may be mechanically arranged similarly to any well-known switches. The movable parts are represented in the rest position with the exception of the contact arms of the selector switches which are in each case represented in connection with a line leading to the next switch.

When the subscriber No. 12345 removes his telephone and wishes to be connected with the subscriber No. 67890 the following

circuit is closed:—ground, battery G' , coil 1 of the call relay R , contact 2, branch a of the line contact 3, induction coil 4, microphone 5, branch b of the line, contact 6, 5 coil 7 of the relay R , ground. The relay R is energized and switches the rotary magnet D of the pre-selector at the contact 8 into an interrupter circuit, so that the contact arms 9, 10, 11 are rotated a step at a 10 time. This breaks a circuit from battery G' , contact 18, test relay T , side switch contact 12, test line leading to the connectors, as shown at the preselector of the line 67890 (see contact 87.) A connector testing 15 a line interrupted at 12 will not find connection to the battery which is necessary to energize the connector test relay P over the test contact 83. The opening of contact 12 therefore guards a connection 20 against calls over connectors. In addition, at the first step contact 18 is opened and contact 17 closed. The relay R connects the arm 11 through contact 13 with the battery and ground through the meter Z 25 and the low and high resistance coils of the relay T . As soon as the arm 11 contacts with a free line, the following testing circuit is formed:—ground, battery G' , contact 13, relay T , meter Z , contact arm 11, line c^1 , contacts 14, 15, relay C , end contact k^1 of the switch shaft of the first selector, ground. The relay T in the pre-selector is actuated and disconnects the call relay R and with it the rotary magnet D at 30 the contacts 2 and 6. The pre-selector therefore remains stationary at the sought line a^1, b^1, c^1 . Further, the relay T short-circuits its high resistance coil at the contact 16, whereby the sought line a^1, b^1, c^1 35 is occupied, and the above-mentioned testing circuit, after opening the contact 18, continues to remain as a holding circuit over the ground, battery G' , contacts 17, 16, low resistance coil of relay T , meter Z , contact 11 and so on. The current is so weak 40 that the meter is not actuated. Lastly, the relay T connects the calling subscriber over the contacts 19 and 20, the contact arms 9 and 10 and the lines a^1 and b^1 with 45 the repeating relays A^1 , X and B^1 . The following circuit is at once formed:—ground, battery G' , relay A^1 , one coil of relay X , branch a , subscriber's station, branch b , the second coil of relay X , relay 50 B^1 to ground. The relays A^1 and B^1 are actuated but not the relay X at first, because this is differentially wound. 55 By means of contact 21 the relay B^1 bridges over contact 15 which is at present 60 still closed: in addition, this relay closes the following circuit:—ground, battery G' , contact 22, contact 23, relay V , contact 24, ground. The relay V closes a contact 25 in parallel with contact 23 and opens contact 14 whereby the low resistance coil of

the relay C^1 is connected into the above-mentioned holding circuit of the relay T of the pre-selector and of the relay C of the first selector. The relay C^1 is energized, opens the contacts 15 and 23, and at contact 26 connects its high resistance coil in parallel with the relay C of the first selector. The two coils of the relay C^1 are so connected that their actions support one another. The relay V , in addition, connects the meter relay Zr on the one hand by way of its contact 65 to ground, and on the other hand by way of the contact 64 to the line b^1 . This line b^1 is separated from the line b_1 , and the line a^1 from the line a_1 by condensers 166 and 167, respectively. Now when the calling subscriber brings his numbered dial out of its rest position in order first to select the numeral 6, the contacts 126 and 27 are closed, whereby the lines a and b are grounded. The differential relay X is hereby actuated and closes the following circuit:—ground, battery, resistance 28, contact 29, point 30 of the right-hand coil of the relay X and from here 35 firstly by way of the relay B^1 to ground, and secondly over the right-hand coil of the relay X , line b^1 , contact arm 10, contact 20, line b , contact 26, contact 27 and ground. This current in the line b and b^1 flows in a 40 direction opposite to the previous direction, so that the actions of the currents in the two coils of relay X now aid one another. This relay disconnects the meter relay Zr from the line b_1 at the contact 64 and then 45 closes a circuit from ground by way of the battery G' , contact 31, line b_1 , contact 32, relay B in the first selector to ground. 50 When the subscriber allows his dial to run back from number 6, the circuit is 55 broken six times in succession at contact 3, the repeating relay A^1 becomes currentless each time and on its part each time closes a circuit from ground and battery G' over the contacts 33 and 34, line a_1 , contact 35, relay 60 A to ground. The relay A imparts the impulse by means of contact 36 to the lifting magnet H of the first selector. The switch shaft with the contact arms 37, 38, 39 is hereby 65 lifted six steps. At the first step the head contact k^1 opens, but this brings about no changes as the relay C has previously closed a parallel contact 40; in addition, the head contact k^2 is closed at the first step, whereby the connection into circuit of the rotary 70 magnet D is prepared. When the dial has again reached its rest position the original state is again brought about in the subscriber's line, the relay X becoming currentless and releasing its armatures. Simultaneously, the relay B in the first selector 75 also becomes currentless and connects the rotary magnet D into the following circuit:—ground, battery G' , interrupter U , rotary magnet D , contacts 41, 42, 43, head 80

contact k^2 , ground. The switch shaft rotates until, when a contact arm contacts with a free line, a current flows in the following circuit:—ground, contact 44, high and low resistance coils of the testing relay P, contact arm 39, conductor c^2 , relay C in the second selector, head contact k^1 , battery G', ground. The relay P is energized, disconnects the rotary magnet D at contact 42, so that the selector remains stationary at the sought line a^2 , b^2 , c^2 , and short-circuits the high resistance coil of relay P over ground, head contact k^2 , contacts 43 and 45, whereby the sought line is locked. The current for relay P remains during the continuance of the connection. In addition, the relay P disconnects the relays B and A from the lines a , b at the contacts 32 and 35, respectively, and connects the relays A and B of the second selector over the contacts 46 and 47 into the circuit of the contact arms 37 and 38, lines a^2 and b^2 and contacts 48, 49. The relay C of the second selector connects, among others, the contact 50 in parallel with the head contact k^1 as in the first selector.

The connection and arrangement of the second selector is the same as in the first selector except that the relay C in the second selector is connected to the battery, whereas in the first selector it is directly grounded. Accordingly, the second selector is set in the same manner as the first selector. When the subscriber rotates his dial a second time to the numeral 7, the differential relay X is again energized and with it the relay B of the second selector while the dial rotates. Then when the dial returns and the relay A^1 receives impulses, these are transferred to the relay A of the second selector and hereby to the lifting magnet H. The shaft of the second selector is consequently lifted seven steps. At the first step the head contact k^1 is opened and the head contact k^2 closed. After the dial has run down the relay X and the relay B of the second selector are deenergized, and the rotary magnet D of the second selector receives impulses, whereby the contact arms 51, 52, 53 are rotated. When a free line is contacted the following circuit is established:—ground, contact 54, high and low resistance coils of the testing relay P, contact arm 53, conductor c^3 , relay C in the third selector, the releasing magnet M, battery G', ground. The releasing magnet is not actuated as the current is too weak. The testing relay P in the second selector is actuated, disconnects the relays A, B, and the rotary magnet D and short-circuits its high resistance winding exactly as in the first selector. The current for the relays P and C remains during the continuance of the connection as in the first selector. After the relay P in the second selector has been actuated the lines a^2 , b^2 are connected over the contacts 55, 56,

contact arms 51, lines a^3 b^3 and contacts 57, 58 with the relays A and B in the third selector.

The third selector could be connected just as the second selector as it operates in the same manner; the connection of the relay C and the releasing magnet M, however, is preferably modified for the purpose of limiting the number of contacts. The subscriber's dial is now rotated a third time to the numeral 8, whereupon the relay X and the relay B in the third selector are actuated. When the dial returns the repeating relay A^1 receives eight impulses which are transferred in known manner in the third selector to the relay A and the lifting magnet H. The switch shaft of the third selector is lifted eight steps. At the first step the head contact k closes, the other head contact being omitted. This closure of the contact k at first has no influence on the circuit of the relays C and M as the contact 59 of the relay C has been previously opened. When the dial has run down and the relay X and the relay B in the third selector are deenergized, the rotary magnet D receives impulses from the interrupter U until, on contacting with a free line a^4 , b^4 , c^4 , the following circuit is established:—ground, contact 60, high and low resistance coils of the testing relay P, contact arm 63, conductor c^4 , head contact k^1 in the connector, relay C, battery G' and ground. The testing relay P and the relay C in the connector are actuated and remain energized during the continuance of the connection. The testing relay P disconnects the repeating relays A, B and the rotary magnet D as in the first and second selectors, locks the sought line c^4 by short-circuiting the high resistance coil of the testing relay P, and connects the lines a^3 and b^3 by way of the contacts 66, 67, the contact arms 61, 62, lines a^4 , b^4 , and the contacts 68, 69 with the relays A and B in the connector. At the same time as the relay C in the connector is energized the auxiliary relay E in the connector is energized in the following circuit:—ground, head contact k^2 , contacts 70, 71, relay E, battery G', ground. This relay E closes a contact 72 parallel with the head contact k^2 , so that the relay E remains energized even after the contact k^2 has been opened when the switch shaft rises. The relay E connects the relay A by the contact 73 with the ground. Now when the subscriber rotates his dial to number 9, the relay X is actuated during the continuance of the rotation of the dial and also the relay B in the connector. When the dial returns the repeating relay A^1 receives nine impulses which are transferred in the connector to the relay A and to the lifting magnet H. The circuit for this magnet is:—ground, contacts 74, 75, magnet H, battery G', ground. The switch shaft rises nine

steps. At the first step the contact k^1 is opened but the relay C holds itself connected in circuit by way of the contact 76. In addition, the contact k^2 is opened and the contact k^3 closed at the first step. Therefore, after the dial has run down and the relays X and B are currentless, the following circuit is closed:—ground, head contact k^3 , contacts 77, 78, auxiliary relay F, battery G', ground. The auxiliary relay F is actuated and holds itself energized by means of the contact 79 even after the contact 77 has been opened. The last rotation of the dial by the subscriber to the cipher 0 now takes place, whereupon the relay X and the relay B in the connector are actuated during the continuance of the rotation of the dial. As the contact 79 is closed the relay B now energizes the auxiliary relay G in the following circuit:—ground, contacts 79, 84, auxiliary relay G, battery G', ground. All the three auxiliary relays E, F and G are now energized. On the dial returning, the repeating relay A¹ receives ten impulses which are transferred in the connector to the relay A. As the relay F has been energized in the meantime, the relay A now transfers its impulses to the rotary magnet D, instead of to the lifting magnet H, in the following circuit:—ground, contacts 74, 80, rotary magnet D, battery G', ground. The contact arms 81, 82, 83 are rotated ten steps and thereby connected with the desired subscriber's line. When the relay X and the relay B in the connector become currentless at the end of the rotation of the dial, for the purpose of testing the required subscriber's line the following circuit is made:—contact arm 83, low and high resistance coils of relay P, contacts 85, 86, ground. When the required subscriber's line is free current flows in the following circuit:—ground, contacts 86, 85, high and low resistance coils of relay P, contact arm 83, conductor c', contact 87 in the preselector of the called subscriber, meter Z', low and high resistance coils of relay T', contact 88, battery G', ground. The relay P in the connector and the relay T' in the pre-selector of the called subscriber (but not the meter Z') are actuated and remain energized during the continuance of the entire connection. The relay T' separates the call relay R' from the subscriber's line a', b' at the contacts 89, 90. By means of the contacts 91, 92 the relay P in the pre-connector bridges the supervisory relay Y over the battery G' between the contact arms 81 and 82. The relay Y is, however, not at present actuated, because a condenser is connected in circuit at the subscriber's station. The relay P closes a second circuit over the contacts 93, 94 to ground for the already energized relay G, so that this relay remains energized when the other path, i. e. ground and contacts 79, 84, is subsequently broken. Namely, when the relay B in the connector is deenergized for the last time it opens at contact 95 the circuit for the auxiliary relay E, as contact 70 is held open by the auxiliary relay G. The relay E is deenergized and, as long as the shaft is lifted, cannot be connected in circuit again as the contact k^2 is open. The relay E also disconnects the relay A at contact 73, so that the subscriber can no longer actuate the connector by rotating his dial. By means of the contact 78 the relay E also breaks the circuit for the slow-acting relay F. So long as this relay F retains its armature the call-bell relay L is energized in the following circuit:—ground, battery G', relay L, contacts 96, 97, 98, ground. The relay L is therefore energized as long as the contact 98 is closed and by tilting over the levers 99, 100 sends the first call-signal to the desired subscriber. When the armature of the slow-acting relay F has completely fallen down, the call-bell relay L is connected at contact 101 to a switching device 102 which periodically closes the circuit for this relay L, whereby the same is energized each time and sends additional call-signals. Each time the relay L is energized it sends to the calling subscriber a "disengaged" signal along the following circuit:—ground, coil 118 of the buzzer, contact 119, condenser 110, contact 111, relay A, contact 68, line a to the calling subscriber, line b, contact 69, relay B, ground. After the armature of the relay F has fallen down, this relay short-circuits the high resistance coil of the relay P by its contact 117, so that the desired subscriber's line is locked. When the called subscriber answers by removing his receiver, the relay Y is energized and by means of its contacts 68, 69 disconnects the relays A, B and closes the talking circuit at the contacts 103, 104. The relay Y also interrupts at the contact 94 the current for the relay G, so that the latter is deenergized and disconnects the call-bell relay L at the contact 96. Further, the relay Y closes the contact 116, so that the current for the relays P and T' now flows over the contacts 117 and 116 instead of over the contact 86. At this moment metering takes place. A part of the current flowing by way of ground, battery G', relay Y, contacts 100 and 92 flows by way of the contact 104, line b⁴, contact arm 62, contact 67, line b³, contact arm 52, contact 56, line b², contact arm 38, contact 47, line b¹, contact 64 meter relay Zr, contact 65, to ground. The relay Zr is energized and by closing the contact 105 it increases the holding current flowing since the beginning over the relay T and meter Z in such manner that the meter Z is now actuated. In addition, the relay Zr breaks at the contact 24 the circuit, closed formerly, for the slow-acting relay F.

relay V. This relay therefore slowly releases its armature, whereupon the contacts 25 and 65 are opened after some time and the contact 14 is closed. When the contact 65 is open, the meter relay Z_r is disconnected from the talking line b , and the heavier current for the meter Z is interrupted at the contact 105. The relay V cannot, however, be energized again after the contact 24 has been closed, because the contacts 23 and 25 are open. The low resistance coil of relay C^1 is kept energized, however, as before, by way of the contact 26 and the high resistance coil of this relay. After the meter relay Z_r has been disconnected the conversation can be at once commenced. The microphone of the calling station is fed by way of the relays A^1 , B^1 and X , and the microphone of the called station by way of the relay Y in the connector. The two feeding circuits are separated from one another by the condensers 66 and 67.

When the required subscriber's line is busy, after the contact 85 has been closed the testing relay P is not actuated and therefore the relay Y is not connected at the contacts 91 and 92 to the required subscriber's line. Further, the call-relay L is not connected into circuit at contact 97. Lastly, the holding circuit for the relay G is not closed at the contact 93. Therefore, when the relay B becomes currentless and the contact 95 opens, the armatures of all three auxiliary relays E, F and G fall back in turn into the rest position. The relay E breaks the circuit for relay F at contact 78, and relay F the circuit for relay G at contact 79. The calling subscriber now receives a lasting buzzer current which flows from ground by way of the coil 107 of the buzzer, contacts 108, 109, condenser 110, contact 111, relay A, contact 68, branch a to the subscriber and by way of the branch b back by way of contact 69, relay B and ground. When the subscriber hears this engaged signal he should replace his receiver, whereupon the connection is done away with as described hereinafter.

It is to be noted that, after the armature of the relay G has fallen, the testing relay P is cut out at contact 86, so that this relay P cannot be subsequently energized again if the called line should in the meantime become free. In addition, in this event no metering takes place as the circuit for the meter relay Z_r is not closed at contact 104.

When the calling subscriber replaces his receiver after the conversation, the relays A^1 and B^1 become currentless. By opening the contact 21 (contact 15 is open) the relay B^1 disconnects the relay C in the first selector. The holding current for relay T flowing since the beginning must therefore

70 G', contacts 17, 16, low resistance coil of relay T, meter Z, contact arm 11, contacts 14, 26, high resistance coil of relay C^1 , ground. Owing to the high resistance of the relay C^1 the current is weakened to such an extent that the relay T releases its armature, whereupon the circuit for relay C^1 and relay T is automatically broken at contact 16. The relay C^1 therefore becomes currentless together with relay T. Thereby 75 the circuit for rotary magnet D of the pre-selector is closed again as follows: ground, interrupter U, rotary magnet D, contact 121, contact 17, battery G' ground. As soon as the contact arms of the thus rotated pre-selector reach the normal position, contact 17 opens, and contact 18 closes. The circuit of the rotary magnet D is therefore broken at 17. The pre-selector now returns in known manner into its zero position. 80

When the armature of the relay C in the first selector is released the releasing magnet M is connected into the following circuit:—ground, end contact h^2 , contact 43, magnet M, battery G' , ground. This magnet returns the switch shaft in known manner into its rest position. The circuit is automatically finally broken at the contact h^2 , while at the contact h^1 the relay C is connected with the ground, whereby the first selector is again accessible for further calls. 85 The relay C breaks, in addition, at the contacts 43, 44 the circuit for the relay P in the first selector and for the relay C in the second selector. The relay P opens the contacts 45, 46 and 47, so that the contact arms are isolated when the switch shaft falls back. Owing to the relay C becoming currentless the second selector is released in the same manner as in the first selector. The current for the relay P is interrupted by the second selector and that for the relay C of the third selector. The relay C of the third selector brings about the release of the third selector and the disconnection of the relay P and of the relay C in the connector. The pre-selector and all the selectors are now released. 90 The connector is released together with the selectors only when the relay Y has not been energized, i. e. in the case of a line being busy or when the called subscriber has not announced himself. If the relay Y has been actuated the circuit:—ground, battery G' , releasing magnet M, contacts 114, 115, head contact h^2 , ground, remains open at 95 contact 115 until the relay Y becomes currentless, i. e. until the called subscriber has also replaced his receiver. When, reversely, the called subscriber replaces his receiver before the calling subscriber, the connector 100 is likewise not released, because the releasing circuit is kept open at contact 114 by the relay C, but the called subscriber becomes free, however, when replacing his re- 105

110

125

opened, when the relay Y becomes currentless, at the contacts 103 and 104 and the current flowing during the conversation for the relays P and T is broken at the contact 5 116.

My invention is not limited to the illustrated embodiment. Particularly, it is not necessary that the impulses for setting the 10 selectors and the connector proceed from one subscriber's station. On the contrary, the invention can also be employed in semi-automatic systems in which operators send the impulses.

I claim:—

15 1. In an automatic telephone exchange system, the combination of subscribers' lines, selector and connector switches adapted to be set by current impulses for establishing a connection between the said lines, devices 20 for connecting a calling line with a free first selector, a repeater located between the said devices and the first selector, devices at the said repeater for holding and breaking the connection, test lines between the said 25 switches, a relay located at the incoming end of the test line of each switch and energized during the connection by a current over the test line, and means for interrupting the said current at the outgoing end of 30 each test line.

2. In an automatic telephone exchange system, the combination of subscribers' lines, selector and connector switches adapted to be set by current impulses for establishing 35 a connection between the said lines, devices for connecting a calling line with a free first selector, a repeater located between the said devices and the first selector, devices at the said repeater for holding and breaking 40 the connection, test lines between the said switches, a relay located at the incoming end of the test line of each switch and energized during the connection by a current over the test line, and means for interrupting 45 the said current at the outgoing end of each test line in every stage of the connection.

3. In an automatic telephone exchange 50 system, the combination of subscribers' lines, selector and connector switches adapted to be set by current impulses for establishing a connection between the said lines, devices for connecting a calling line with a free first selector, a repeater located between the said 55 devices and the first selector, devices at the said repeater for holding and breaking the connection, test lines between each two successive switches, a relay at each end of each test line, a holding circuit for the relays 60 closed over the test line during the connection, and means for breaking the said holding circuit at the selector switch at the outgoing end of the test line.

4. In an automatic telephone exchange 65 system, the combination of subscribers' lines,

selector and connector switches adapted to be set by current impulses for establishing a connection between the said lines, devices for connecting a calling line with a free first selector, a repeater located between the said 70 devices and the first selector and having line relays permanently bridged over the talking line, devices at the said repeater for holding and breaking the connection, test lines between each two successive switches, a relay at each end of each test line, a holding circuit for the relays of said test line, closed over the test line during the connection, and means for breaking the said holding circuit at the selector switch at the outgoing end of 80 the test line; means for keeping energized one of the said line relays during the impulses and during the connection, and means for keeping closed over the attracted armature of the energized line relay the 85 holding circuit for the outgoing test line.

5. In an automatic telephone exchange system, the combination of subscribers' lines, pre-selector, selector and connector switches adapted to be set by current impulses for 90 establishing a connection between the said lines, a preselector for connecting a calling line with a free first selector, a repeater located between the said preselector and the first selector, and having line relays 95 permanently bridged over the talking line, devices at the said repeater for holding and breaking the connection, test lines between each two successive switches, a relay at each end of each test line, a holding circuit for 100 said relays of the test line, closed over the test line during the connection, and means for breaking the said holding circuit at the selector switch at the outgoing end of the test line; means for keeping energized one 105 of the said line relays during the impulses and during the connection, and means for keeping closed over the attracted armature of the energized line relay the holding circuits of the test line going out from the 110 repeater and of the test line coming in from the pre-selector.

6. An automatic telephone exchange system comprising in combination, subscribers' 115 lines, selector and connector switches adapted to be set by current impulses for establishing a connection between the said lines, a set of repeating relays having line relays permanently bridged over the talking lines, test lines between each two successive switches, 120 a relay at each end of each test line and energized by a current over the test line, and means at the relay at the incoming end of the test line for interrupting the current over the test line going out from its switch 125 to the successive switch.

7. A telephone system, comprising in combination, subscribers' lines, automatic switches adapted to be set by impulses for establishing a connection between subscrib- 130

ers' lines, a set of repeating relays having line relays permanently bridged over the talking lines, test lines between each two successive automatic switches, a relay located at each end of each test line and energized by a current over the test line and over a make contact of the relay at the incoming end of the test line.

8. An automatic telephone exchange system, comprising in combination, subscribers' lines, automatic switches adapted to be set by impulses for establishing a connection between subscribers' lines, a set of repeating relays having line relays permanently bridged over the talking lines, test lines between each two successive automatic switches, a relay at each end of the test lines energized by a current over the test line, means at the relay at the incoming end of the test line for interrupting the current over the test line going out from its switch to the successive switch, and means at the incoming end of the test line for keeping it interrupted until the switch at this end has returned to its normal position.

9. A telephone system, comprising in combination, telephone lines, pre-selector, selector and connector switches, a set of repeating relays, means at the repeating relays for holding and breaking the connection, test lines between each two successive switches, a relay located at each end of the test line of each switch and energized by a current over the test line, means for interrupting said current over the test line at each stage of the connection, two operating magnets and one releasing magnet at each selector switch, a circuit for one of the operating magnets over a make contact of the said relay at the incoming end of the test line, and a circuit for the releasing magnet over a break contact of the said relay.

10. An automatic telephone system, comprising in combination, subscribers' lines, pre-selector, selector and connector switches, a repeater, one relay of said repeater having means for separating the calling and the called halves of the connection during the impulses, and means for energizing the said relay before the impulses start and until the impulses stop.

11. An automatic telephone system, comprising in combination, subscribers' lines, pre-selector, selector and connector switches,

a repeater, a differential relay at said repeater having means for separating the calling and the called halves of the connection during the impulses, said differential relay having one coil connected to each branch of the calling line, and means for grounding one branch of the calling line before starting the impulses and keeping it grounded until the impulses stop.

12. An automatic telephone exchange system, comprising in combination, a calling line and a called subscriber's line, a connector switch for completing the talking connection between the said lines, selector switches for connecting the calling line with the connector switch, a test line from the last selector switch to the connector switch, a relay at the connector in the test line, a holding circuit for the said relay, means at the last selector switch for breaking the said holding circuit, a test line between the connector switch and the called line, a test relay at the connector for testing the called line, a holding circuit for the test relay over the test line of the called line found to be free, operating magnets and a releasing magnet at the connector, relays at the connector at the talking lines coming from the last selector, a supervisory relay at the connector for the called line, a slow-acting relay and two switching relays at the connector, holding circuits for these latter three relays, means at the connector for energizing the slow-acting relay at the commencement of the unit impulses and deenergizing the same at the termination thereof, means at the connector for closing the holding circuit of the one switching relay when the connector is occupied and breaking the same at the termination of the impulses for the operating magnets of the connector, and means at the connector for establishing the holding circuit for the second switching relay at the commencement of the last series of impulses and breaking the same when the called subscriber answers.

In testimony whereof I sign my name to this specification in the presence of two witnesses.

FRIEDRICH MERK.

Witnesses:

HENRY HASPER,
ARTHUR SCHROEDER.
